Primary Examiner — John R Yeh(74) *Attorney, Agent, or Firm* — Knobbe, Martens, Olson & Bear, LLP(57) **CLAIM**

The ornamental design for a puck antenna module, as shown and described.

DESCRIPTION

FIG. 1 is a perspective top left view of a puck antenna module according to the present invention;

FIG. 2 is a front elevational view thereof;

FIG. 3 is a rear elevational view thereof;

FIG. 4 is a top plan view thereof; and,

FIG. 5 is a left side elevational view showing the puck antenna module in use, mounted on a roof of a vehicle.

The left side elevational view of the puck antenna module is identical to the front elevational view thereof. The right side elevational view of the puck antenna module is identical to the rear elevational view thereof.

The broken lines shown in FIG. 5 illustrate environmental subject matter only, such as a roof of a vehicle, and form no part of the claimed design.
